Primary Examiner — Charles D Hanson*(74) Attorney, Agent, or Firm* — Dorsey & Whitney LLP**(57) CLAIM**

The ornamental design for a medical implant, as shown and described.

DESCRIPTION

FIG. 1 is a perspective view of a new design for a medical implant;

FIG. 2 is a right side elevational view thereof, the left side elevational view being a mirror image;

FIG. 3 is a rear elevational view thereof;

FIG. 4 is a front elevational view thereof;

FIG. 5 is a top plan view thereof; and,

FIG. 6 is a bottom plan view thereof.

The broken lines represent portions of the medical implant that form no part of the claimed design.

Any combination of the illustrated features, including claimed features and non-claimed features, may be claimed in this application or a continuing application claiming priority to this application by converting any portion of the broken lines to solid lines, any portion of the solid lines to broken lines, or both.
